UNITED STATES PATENT OFFICE.

JOHN S. CUMMINGS, OF NEW YORK, N. Y., ASSIGNOR, BY MESNE ASSIGNMENTS, TO EASTMAN KODAK COMPANY, OF ROCHESTER, NEW YORK, A CORPORATION OF NEW YORK.

PHOTOGRAPHIC-PRINTING APPARATUS.

SPECIFICATION forming part of Letters Patent No. 762,468, dated June 14, 1904.

Application filed October 23, 1902. Serial No. 128,412. (No model.)

To all whom it may concern:

Be it known that I, JOHN S. CUMMINGS, a citizen of the United States, residing at New York, county of Kings, and State of New York, have invented certain new and useful Improvements in Photographic-Printing Apparatus, fully described and represented in the following specification and the accompanying drawings, forming a part of the same.

- 10 This invention relates to improvements in photographic-printing apparatus of the class shown and described in my prior application, filed September 10, 1901, Serial No. 74,887—that is to say, photographic-printing apparatus comprising negative-supporting means and a light-supporting frame which are relatively adjustable to and from their support and longitudinally thereof in a right line and the negative-supporting means which is also 15 angularly adjustable to and from the support and longitudinally thereof, the purpose of these several adjustments being to provide for the proper printing of negatives of different sizes and densities and negatives different 20 portions of which vary in density.

The photographic-printing apparatus of the present invention, like that of my said prior application, is designed particularly for use by professional photographers and for printing by artificial light, though it may be used by amateurs and certain parts of it may be used for printing by natural light.

In the accompanying drawings, Figure 1 is a perspective view of a photographic-printing apparatus embodying the present invention. Fig. 2 is a longitudinal section of the same. Fig. 3 is an end view looking toward the left of Fig. 2, electric-light fittings being substituted for the gas-fittings of the latter figure. Fig. 4 is a rear view of the printing-frame. Fig. 5 is a section of the same on the line 5 of Fig. 4; and Fig. 6 is a plan view of the printing-frame, its carrier, and the support on which the latter is mounted.

45 Referring to said drawings, 1 represents the printing-frame, 2 its carrier, and 3 the support on which the latter is mounted. The printing-frame shown consists of a frame 4,

having a sectional hinged back 5 and provided with adjustable members or bars 6 50 for engaging the negative 8 and holding it against the glass plate 9 in printing position. Any other suitable form of printing-frame may be employed without departing from the present invention. At the opposite end of the support 3 is provided a light-supporting frame 10, provided with fixtures 11, adapted to receive Welsbach or other burners 12 and flexible gas-piping 13, as shown in Figs. 1 and 2, or incandescent lamps 12^a and electric-light 55 wires 13^a, as shown in Fig. 3.

The printing-frame 1 is adapted to receive negatives of different sizes, and in order to properly print from such negatives it is necessary that the frame 1 and light-supporting 60 frame 10 should be relatively adjustable vertically or to and from support 3. The member which is adjustable in the present case is the light-supporting frame 10. To provide for this adjustment, it is mounted on a pair of 65 standards 14, secured to support 3 and on which it is free to slide vertically, set-screws 15 being provided for securing it to the standards in its position of adjustment. Provision is also made for angular adjustment or swing 70 of the printing-frame both horizontally or longitudinally of the support 3 and vertically or to and from the support, the purpose of such angular horizontal adjustment of the printing-frame being to bring denser portions 75 of a negative (considered widthwise of the frame) closer to the light than other portions, while the purpose of such vertical angular adjustment is to bring denser portions of a negative (considered vertically of the frame) 80 closer to the light.

The horizontal angular adjustment referred to of the printing-frame 1 is provided for in the present case by pivotally mounting the printing-frame carrier 2 on the support 3 so 90 that it may swing horizontally thereon, as shown in Fig. 6. This pivotal mounting of the carrier 2 may be secured in many ways; but I prefer the simple means shown, consisting of a bolt 16, projecting upward through 95 an opening in support 3 and passing through

an opening in the base of the carrier 2, the upper end of said bolt being threaded to receive a thumb-nut 17, by which the carrier 2 is held to the support and also locked in any position thereon to which it may be adjusted. The support may and preferably will be provided with a second opening and bolt 16^a nearer the light-supporting frame for use should occasion require it.

10 To provide for the vertical angular adjustment referred to of the printing-frame 1, the latter is horizontally pivoted in vertical standards 18 of its carrier 2, so that the frame may be swung to and from the support 3 into any 15 angular position desired, as shown in Figs. 1 and 2. This pivotal connection of the printing-frame 1 in the present case is provided not only for the purpose of angularly adjusting the frame and its negative relatively to 20 the light, but also for the purpose of enabling the operator to swing the frame 1 to a substantially horizontal position (see Fig. 2) with its rear side upward, so that he can conveniently and quickly remove from the frame the 25 sheets of photographic-printing paper as printed and keep the frame supplied with sheets to be printed upon. This is a feature of considerable importance, as the printing-paper of the present day is very rapid, and 30 with a frame capable of being swung into the convenient position shown a great saving of time is effected and the product of the printing apparatus may be materially increased.

It is desirable when the frame 1 is swung 35 to the horizontal position shown that some means be provided for holding and steadyng it in that position. Means for this purpose are shown in the present case, consisting of a stop 19 on an arm 20, secured to one of the 40 standards 18 of carrier 2 and which engages and arrests the downward movement of the printing-frame when swung to this horizontal position, upward movement of the frame from this position being prevented by a pin 45 21, which as the frame is swung downwardly presses the arm 20 (which is of spring metal) to one side and as the frame reaches horizontal position enters an opening 22 in said arm, as shown in Fig. 2. The frame 1 is released in order to return it to or toward vertical position by the operator pressing the 50 spring-arm 20 to one side, thus releasing pin 21 from opening 22, the frame being then free to be swung upward.

55 As the frame 1 will in printing from one negative be several times swung from printing position to horizontal position, (for removal of prints,) it is desirable, of course, in order to secure uniformity in the several 60 prints made from it that the frame should be returned with certainty to the same angular position relatively to the light each time a printed sheet is removed and another to be printed is inserted in the frame. Means are 65 provided for this purpose, in the present case

consisting of an adjustable stop 23, sliding in a slot 24 in arm 20 and provided with a thumb-nut 24, by which it is locked in its adjusted position on the arm. In printing from a negative the proper angular position of the frame will be first ascertained and the stop 23 adjusted and locked to arm 20, so as to engage the front face of the frame in that position, as shown in Figs. 1 and 2. Thereafter each time a fresh sheet is inserted in the frame when the frame is swung from horizontal position by the operator it will be arrested by the stop 23 in the proper angular position for printing. When a new negative is inserted in the frame, the stop 23 will of course be readjusted, if necessary.

Between the frame 1 and light-supporting frame 10 is interposed a shutter or apron 25, having a panel preferably of orange paper, said shutter being mounted so as to move vertically in a guideway formed in a frame 26 and consisting of strips 27, engaging one side of the shutter, and antifriction-rollers 28, engaging the opposite side thereof, as shown in Fig. 2. The shutter 25 is moved downwardly 85 by its own weight and is moved upwardly by means of a cord 29, having a handle 30 at its free end and passing around a pulley 31 on support 3, thence around a pulley 32, fast to shaft 32^a, journaled in the upper end of frame 90 26, thence through eyes 33 34 fast on the shutter, and around a second pulley 35 on shaft 32^a and to which the opposite end of the cord is connected. A pull on cord 29 rotates shaft 32^a and raises the shutter, which 95 remains in its raised position, Fig. 1, until the operator releases the cord, when the shutter is returned to its lowermost position, Fig. 2, by gravity, aided, if desired, by a spring. (Not shown.)

100 The shaft 3 is preferably provided on opposite sides with walls 36 in line with the light, which serve as light-guards protecting the paper from the action of the light, the developing-tray being located to one side of the 105 printing apparatus in convenient position for the operator to place his prints therein as he removes them from the frame.

What is claimed is—

1. In a photographic-printing apparatus, the 115 combination of a suitable support, and negative-supporting means adjustable to different printing positions angularly to and from the support, substantially as described.

2. In a photographic-printing apparatus, the 120 combination of a suitable support, and negative-supporting means adjustable to different printing positions angularly to and from and also longitudinally of the support, substantially as described.

3. In a photographic-printing apparatus, the 125 combination of a suitable support, and a light-supporting frame and negative-supporting means relatively adjustable to and from the support rectilinearly, said negative-support- 130

ing means being also adjustable to different printing positions angularly to and from the support, substantially as described.

4. In a photographic-printing apparatus, the combination of a suitable support, and a light-supporting frame and negative-supporting means relatively adjustable to and from the support rectilinearly, said negative-supporting means being also adjustable to different printing positions angularly to and from and also longitudinally of the support, substantially as described.

5. In a photographic-printing apparatus, the combination of a suitable support, a printing-frame carrier angularly adjustable longitudinally of the support, and a printing-frame mounted on said carrier and adjustable thereon to different printing positions angularly to and from the support, substantially as described.

6. In a photographic-printing apparatus, the combination of a suitable support, a printing-frame carrier angularly adjustable longitudinally of the support, a printing-frame mounted on said carrier and angularly adjustable thereon to and from the support, and an adjustable stop for arresting the movement of the frame to angular position, substantially as described.

30 7. In a photographic-printing apparatus, the combination of a suitable support, a printing-frame carrier angularly adjustable longitudinally of the support, a printing-frame mounted on said carrier and angularly adjustable thereon to and from the support, means for locking the carrier in its positions of adjustment, and an adjustable stop for arresting the movement of the frame to angular position, substantially as described.

40 8. In a photographic-printing apparatus the combination with a suitable support, of a printing-frame angularly adjustable thereon vertically to different printing positions, substantially as described.

45 9. In a photographic-printing apparatus the combination with a suitable support, of a printing-frame angularly adjustable thereon vertically, and an adjustable stop for arresting the movement of the frame to angular position, substantially as described.

50 10. In a photographic-printing apparatus the combination with a suitable support, of a printing-frame mounted thereon to move from printing position toward a horizontal position with its rear side uppermost and angularly adjustable vertically to different printing positions, substantially as described.

55 11. In a photographic-printing apparatus the combination with a suitable support, of a printing-frame mounted thereon to move from printing position toward a horizontal position with its rear side uppermost, and means for locking it in the latter position, substantially as described.

12. In a photographic-printing apparatus 65 the combination with a suitable support, of a printing-frame mounted thereon to move from printing position toward a horizontal position with its rear side uppermost, and means for automatically locking it in the latter position, substantially as described.

13. In a photographic-printing apparatus the combination of a suitable support, a printing-frame carrier angularly adjustable longitudinally of the support, a printing-frame 75 mounted on the carrier to move from printing position toward a horizontal position with its rear side uppermost, and means carried by the carrier for locking it in the latter position, substantially as described.

80 14. In a photographic-printing apparatus the combination of a suitable support, a printing-frame carrier angularly adjustable longitudinally of the support, a printing-frame mounted on the carrier to move from printing position toward a horizontal position with its rear side uppermost, and means carried by the carrier for automatically locking it in the latter position, substantially as described.

85 15. In a photographic-printing apparatus 90 the combination with a suitable support, of a printing-frame angularly adjustable thereon vertically to different printing positions and also adapted to swing from printing position toward a horizontal position with its rear side 95 uppermost, substantially as described.

16. In a photographic-printing apparatus the combination with a suitable support, of a printing-frame angularly adjustable thereon vertically to different printing positions and also adapted to swing from printing position 100 toward a horizontal position with its rear side uppermost, said support being provided with adjustable means for arresting the angular movement of the frame to printing position 105 and with means for locking it when swung from that position toward the horizontal with its rear side uppermost, substantially as described.

17. In a photographic-printing apparatus 110 the combination with a suitable support, of a printing-frame angularly adjustable thereon vertically to different printing positions and also adapted to swing from printing position 115 toward a horizontal position with its rear side uppermost, said support being provided with adjustable means for arresting the angular movement of the frame to printing position and with means for automatically locking it 120 when swung from that position toward the horizontal with its rear side uppermost, substantially as described.

18. In a photographic-printing apparatus the combination with a suitable support, of a carrier angularly adjustable thereon horizontally, and a printing-frame angularly adjustable thereon vertically to different printing positions and also adapted to swing from print-

ing position toward a horizontal position with its rear side uppermost, substantially as described.

19. In a photographic-printing apparatus the combination with a suitable support, of a carrier angularly adjustable thereon horizontally, and a printing-frame angularly adjustable thereon vertically to different printing positions and also adapted to swing from printing position toward a horizontal position with its rear side uppermost, said support being provided with adjustable means for arresting the angular movement of the frame to printing position and with means for locking it when swung from that position toward the horizontal with its rear side uppermost, substantially as described.

20. In a photographic-printing apparatus the combination with a suitable support, of a carrier angularly adjustable thereon horizontally, and a printing-frame angularly adjustable thereon vertically to different printing positions and also adapted to swing from printing position toward a horizontal position with its rear side uppermost, said support being provided with adjustable means for arresting the angular movement of the frame to printing position and with means for automatically locking it when swung from that position toward the horizontal with its rear side uppermost, substantially as described.

21. In a photographic-printing apparatus the combination of a vertically - adjustable light-supporting frame and negative-supporting means adjustable angularly in horizontal and vertical directions, substantially as described.

22. In a photographic-printing apparatus the combination of a vertically - adjustable light-supporting frame, a carrier adjustable angularly in a horizontal direction and a printing-frame adjustable thereon angularly in a vertical direction, substantially as described.

23. In a photographic-printing apparatus the combination of a suitable support, a light-supporting frame, negative - supporting means, a shutter interposed between said frame and negative-supporting means, and a vertical guideway for said shutter mounted on said support independently of said frame

and negative-supporting means, substantially as described.

24. In a photographic-printing apparatus the combination of a suitable support, a light-supporting frame, negative - supporting means, a shutter interposed between said frame and negative-supporting means, and a vertical guideway including antifriction-rollers for said shutter mounted on said support independently of said frame and negative-supporting means, substantially as described.

25. In a photographic-printing apparatus the combination of a suitable support, a light-supporting frame, negative - supporting means, a shutter interposed between said frame and negative-supporting means, a vertical guideway for said shutter mounted on said support independently of said frame and negative-supporting means, and means for operating the shutter comprising shaft 32^a and a cord free at one end, passing over said shaft and through suitable guiding means on the shutter, and secured at its opposite end to said shaft, substantially as described.

26. In a photographic-printing apparatus the combination of a shutter, a suitable guideway therefor, and means for operating the shutter comprising shaft 32^a and a cord free at one end, passing over said shaft and through suitable guiding means on the shutter and secured at its opposite end to said shaft, substantially as described.

27. In a photographic-printing apparatus the combination of a suitable support, a light-supporting frame, negative - supporting means, a shutter interposed between said frame and negative-supporting means, a vertical guideway for said shutter mounted on said support independently of said frame and negative-supporting means, and light-guards, as 36, extending from the shutter and inclosing the light-supporting frame, substantially as described.

In testimony whereof I have hereunto set my hand in the presence of two subscribing witnesses.

JOHN S. CUMMINGS.
